UNITED STATES PATENT OFFICE.

FRANK W. STEINACKER, OF CLEVELAND, OHIO.

BOBBIN FOR SPINNING-MACHINES.

1,204,517.

Specification of Letters Patent. Patented Nov. 14, 1916.

Application filed March 8, 1915. Serial No. 12,723.

To all whom it may concern:

Be it known that I, FRANK W. STEINACKER, a citizen of the United States, residing at Cleveland, in the county of Cuyahoga and State of Ohio, have invented certain new and useful Improvements in Bobbins for Spinning-Machines, of which the following is a specification.

This invention relates to an improvement 10 in bobbins for spinning machines, and the improvement comprises a metal bobbin having a rigid body of extremely light weight and a yarn or thread-winding surface provided with relatively minute pits or pockets 15 of multiform irregularly distributed thereover.

The bobbins commonly used in spinning machines consist of wood. In many instances these are subjected to extreme 20 changes in temperature, and sometimes moisture, which occasions warping or checking of the surface. For that reason, and also other reasons, the life or utility of a wooden bobbin is limited.

25 My object is to provide a metal bobbin which will outwear ten or more wooden bobbins and which is constructed in a particular way to be as light in weight or lighter than a wooden bobbin and also have 30 a winding surface which will retain the yarn or thread during unwinding operations without waste or loss and also without impairing the yarn or thread while being unwound, especially during the final stripping 35 operation of the yarn from the immediate surface of the bobbin.

In the accompanying drawing, Figure 1 is a side view of a spindle and my improved bobbin thereon, and Fig. 2 is a sectional 40 view longitudinally thereof. Figs. 3 and 4 are magnified views, in cross section and plan, of portions of the body and surface of the bobbin.

The bobbin consists of a tubular body 2 45 having an integral head 3 cast of aluminum, zinc or an alloy, an aluminum alloy being preferred because of its characteristic light weight. But I wish to explain at the outset that a bobbin having a body of the necessary strength and cast as light as possible cannot be cast light enough to be of practical service in a spinning machine. In other words a bobbin cast of any metal and as taken from the mold is too heavy and 55 requires further treatment or modification to be of utility, and mere lightness is not

the only requirement as the cast surface is also too slippery to hold the yarn and must be treated or modified also to hold the yarn or thread until the end of operations without working injury to the thread. 60 Consequently, I subject the cast tubular body 2 to a finishing process whereby all the surface portions of the bobbin are pitted and made cellular to a material extent. Preferably, the pits, little hollows or shallow depressions are of all forms or shapes and so numerous and contiguously related that the surface appears rough all over but is not rough actually. In other words, the bobbin 65 has a plane smooth surface with innumerable minute multiform pits or shallow depressions everywhere therein. One way of producing the desired result is by subjecting the bobbin body 2 after it has been cast 70 to the action of an alkali or acid solution for a predetermined length of time. The depth of the pits and the amount of metal dissolved or material removed is important 75 and my present practice is to produce an 80 extensive and widespread pitting of all the surface portions of the body and a material reduction in weight of the original casting. The result is that the bobbin, although made 85 of metal, is reduced materially in weight for practical use on a spinning machine, and the surface of the bobbin, especially the round cylindrical surface over which the thread or yarn is wound, is made porous or 90 perforated with a strippled effect to provide 95 innumerable air pits or pockets adapted to hold the thread or yarn until the end of the winding is reached, such retention of the end windings of the thread or yarn being without excessive strain or undue resistance to affect or injure the thread or 100 yarn. Waste and loss of thread or yarn and imperfections in the woven goods, is thereby avoided and the bobbin, especially a bobbin 105 made of aluminum or non-corrosive metal is not affected by changes in temperature or moisture, and is strong and durable and works great economy in the average mill or spinning factory where such devices are used in great numbers.

The bobbin body 2 is relatively thin over its major length, and has narrow internal annular enlargements 5 and 6, at its upper end and within head 3, see Fig. 2 to provide 110 bearings for the bobbin when slipped over the spindle 7. Head 3 has edge slots 8 to make the usual engagement with the

rotatable spindle. These details of construction and the shape of the bobbin otherwise, may be greatly modified without departing from the spirit and scope of the invention as set forth herein and in the following claims.

What I claim is:

1. A bobbin for spinning machines made of relatively light metal having a multiplicity of minute air pockets over extensive surface areas thereof to effect holding of the yarn thereon during unwinding operations and to further reduce the weight of the bobbin.
- 15 2. A bobbin for spinning machines comprising a tubular body made of relatively light metal and pitted over its thread-winding surface.
- 20 3. A bobbin for spinning machines, comprising a relatively thin tubular metal body having innumerable pits within its surface portions.
- 25 4. A bobbin for spinning machines, comprising a metal tube having an enlarged

head at one end and reduced in its surfaces 25 by an indefinitely large number of minute pockets of various sizes and form.

5. A bobbin for spinning machines comprising a round metal tube having an enlarged end and an indefinitely large number 30 of minute surface depressions over its entire inside and outside surface area.

6. A bobbin for spinning machines comprising a tubular cast metal body having a thread-winding surface provided with innumerable minute multiform pits or cavities 35 in contiguous and wide-spread relations thereover.

7. A bobbin for spinning machines comprising a tubular body made of aluminum 40 reduced everywhere in its surface areas by innumerable pits and depressions.

In testimony whereof I affix my signature in presence of two witnesses.

FRANK W. STEINACKER.
